United States Patent Office

Des. 228,277
Patented Sept. 4, 1973

228,277

HASP

Daniel J. Foote, Wauwatosa, Wis., assignor to
Master Lock Company, Milwaukee, Wis.

Filed May 8, 1972, Ser. No. 251,575

Term of patent 14 years

Int. Cl. D8—07

U.S. Cl. D8—124

FIG - 1

FIG - 2

FIG - 3

FIG. 4

FIG. 5

FIG. 1 is a plan view of a hasp showing the design with the strap in its lowered position;

FIG. 2 is a bottom view thereof;

FIG. 3 is a right hand end view of the hasp with its strap in lowered position;

FIG. 4 is a side view of the hasp with its strap in a position perpendicular to the plane of the hasp plate; and

FIG. 5 is a left hand end view thereof.

I claim:

The ornamental design for a hasp, as shown.
